(57) **CLAIM**

The ornamental design for a calc-slide bone plate, as shown and described.

DESCRIPTION

FIG. 1 is a top perspective view of a calc-slide bone plate comprising the new design;

FIG. 2 is a top view of the design of FIG. 1;

FIG. 3 is a bottom view of the design of FIG. 1;

FIG. 4 is a front elevational view of the design of FIG. 1;

FIG. 5 is a back elevational view of the design of FIG. 1;

FIG. 6 is a left elevational view of the design of FIG. 1, where the right side elevational view is a mirror image thereof.

FIG. 7 is a top perspective view of an alternative embodiment of the calc-slide bone plate of FIG. 1;

FIG. 8 is a top view of the design of FIG. 8;

FIG. 9 is a bottom view of the design of FIG. 8;

FIG. 10 is a front elevational view of the design of FIG. 8;

FIG. 11 is a back elevational view of the design of FIG. 8; and

FIG. 12 is a left elevational view of the design of FIG. 8, where the right side elevational view is a mirror image thereof.

FIG. 13 is a top perspective view of another alternative embodiment of the calc-slide bone plate of FIG. 1;

FIG. 14 is a top view of the design of FIG. 13;

FIG. 15 is a bottom view of the design of FIG. 13;

FIG. 16 is a front elevational view of the design of FIG. 13;

FIG. 17 is a back elevational view of the design of FIG. 13; and,

FIG. 18 is a left elevational view of the design of FIG. 13, where the right side elevational view is a mirror image thereof.

The broken lines shown in the figures represent portions of the calc-slide bone plate that form no part of the claimed design.
